STATIONER'S FLUID APPLICATOR
OR THE LIKE

Everett A. Johnson, Park Ridge, Ill.

Application May 16, 1947, Serial No. 139,081

Term of patent 14 years

(Cl. D74—10)

To all whom it may concern:

Be it known that I, Everett A. Johnson, a citizen of the United States, residing at Park Ridge, in the county of Cook and State of Illinois, have invented a new, original, and ornamental Design for a Stationer's Fluid Applicator or the Like, in which the following is a specification, reference being had to the accompanying drawing, forming part thereof, in which:

Figures 3 and 4 are front and rear views respectively.

I claim:

The ornamental design for a stationer's fluid applicator or the like, substantially as shown and described.

EVERETT A. JOHNSON.
